UNITED STATES PATENT OFFICE

155,418

DESIGN FOR AN EMBOSSED BELT

John R. Hampel, Pewaukee, Wis., assignor to
 Milwaukee Saddlery Company, Milwaukee,
 Wis., a corporation of Wisconsin

Application September 19, 1946, Serial No. 133,396

Term of patent 7 years

(Cl. D3—10)

To all whom it may concern:

Be it known that I, John R. Hampel, a citizen of the United States of America and residing at Pewaukee, in the county of Waukesha and State of Wisconsin, have invented a new, original, and ornamental Design for an Embossed Belt, of which the following is a specification, reference being had to the accompanying drawings, forming a part thereof.

Fig. 1 is an elevational view of the buckle end; and

Fig. 2 is an elevational view of the tail end of an embossed belt, showing my new design.

The belt is of conventional length with parts being broken for convenience of illustration, the dominant features residing in the portions shown in full lines.

I claim:

The ornamental design for an embossed belt, as shown and described.

JOHN R. HAMPEL.
